[57] CLAIM

We claim the ornamental design for the antenna structure, as shown and described.

DESCRIPTION

A description of each of the figures of the drawing is as follows, with the broken line matter being for illustrative purposes only and forming no part of the claimed design: FIG. 1 is an isometric view showing the top, front and left sides of our new design for an antenna structure, shown in full line;

FIG. 2 is a left side elevation view thereof;

FIG. 3 is a rear side elevation view thereof; and,

FIG. 4 is a bottom plan view thereof.

The surfaces of the article not shown in the drawing or described in the specification form no part of the claimed design.
